UNITED STATES PATENT OFFICE.

DON A. RAYMOND, OF MONTICELLO, INDIANA.

FIRE STOP OR TRAP FOR MOTION-PICTURE MACHINES.

Application filed October 13, 1927. Serial No. 225,939.

This invention relates to fire stops or traps of that type used in connection with motion picture machines for the purpose of preventing fire originating in the main casing from 5 entering the magazines of the machine.

The invention has for one of its objects to provide a fire stop or trap of the character stated which shall be adapted to cut off all communication between the main casing and 10 the magazines immediately on the taking fire of that portion of the film passing through the main casing, which shall be simple, durable and inexpensive, and which shall be adapted to be maintained in a state 15 of high efficiency with comparatively little or no attention.

With the foregoing and other objects in view, the nature of which will appear as the description proceeds, the invention consists 20 of the construction, combination and arrangement of parts hereinafter fully described and claimed, and illustrated in the accompanying drawings, wherein:

Figure 1 is a sectional view taken on a 25 plane extending vertically and centrally through a motion picture machine equipped with a fire stop embodying my invention,

Figure 2 is a detail view in side elevation of one of the units of the fire stop or trap, 30 Figure 3 is a sectional view taken on the vertical plane indicated by the line 3—3 of Figure 2,

Figure 4 is a sectional view taken on the vertical plane indicated by the line 4—4 of 35 Figure 3,

Figure 5 is a view in end elevation of the fire stop or trap unit, and

Figure 6 is a sectional view taken on the horizontal plane indicated by the line 6—6 40 of Figure 3.

Referring in detail to the drawings, 1 designates the main casing, 2 the upper magazine, 3 the lower magazine, 4 the objective or front lens, 5 the condenser or rear lens, 45 6 the light shutter of a motion picture machine. 7 designates the upper reel, 8 the lower reel, 9 the film, and 10 the film actuating and guiding means of the machine. The magazines 2 and 3 are provided with 50 slots 11 and 12, respectively, through which the film 9 passes while being unwound from the reel 7 and upon the reel 8.

The fire stop or trap comprises casings 13 which are open at their ends and provided 55 with attaching flanges 14. Each casing 13 is open at one side. The casings 13 are

secured to the magazines 2 and 3 in registration with the slots 11 and 12 to permit the film 9 to pass longitudinally therethrough. The open sides of the casings 13 60 are in registration with the open ends of the slots 11 and 12 in order to permit the film 9 to be readily threaded through the casings.

Gates, each of which consists of an arcuate 65 plate 15 and rollers 16, are arranged within and extend longitudinally of the casing 13. The plates 15 are longer than the casings 13 to position portions of them outwardly 70 beyond the casings. The plates 15 are provided at their inner ends with flanges 17 which extend rearwardly beyond their convex sides and are connected to the rear walls 13^a of the casings 13 by hinges 18. Brackets 19 are secured to the front concave sides 75 of the plates 15 within the casings 13, and they rotatably support the rollers 16. Springs 20 which are arranged between the plates 15 and the rear walls 13^a of the casings 13, function to urge the rollers 16 in 80 the direction of the front walls 13^b of the casing. Brackets 21 are secured to the concave sides of the plates 15 at the free ends of the plates, and journaled in these brackets 85 are tension rollers 22.

The film 9 passes through the casings 13 between the front walls 13^b thereof and the rollers 16 and 22, and said walls are perfectly smooth in order to prevent injury to the emulsion side of the film. While being unwound from the reel 7 onto the reel 8, the film 9 holds the plates 15 in a position to retain the rollers 16 slightly out of contact with the front walls 13^b of the casing 13, whereby to reduce the wear and strain on the film to the minimum. The plates 15 are held in this position against the tension of the springs 20 and as the result of their formation, the arrangement of the tension rollers 22 at their free ends, and the rearward pull exerted on the rollers by the film. When the film breaks, as the result of its taking fire in the main casing 1, or from any other cause, the springs 20 will force the rollers 16 into contact with the front walls 13^b of the casings 13, and as the result 90 the rollers and flanges 17 will close the casings in a manner to cut off all communication between the magazines 2 and 3 and the main casing 1 and those portions of the film in the magazines cannot take fire.

It should be understood that the drawings

are merely illustrative and do not pretend to give exact proportions. Furthermore, the said drawings are illustrative of a preferred construction, it being my expectation that 5 various changes and modifications may be made without departing from the spirit and scope of my invention.

What is claimed is:—

- 10 1. A fire stop or trap for motion picture machines, comprising a casing, a plate extending longitudinally of the casing and projecting beyond one end thereof, a flange on the end of the plate within the casing for contact with one wall of the casing, means pivoting the plate to such wall of the casing, a spring interposed between such wall of the casing and the plate, rollers 15 journaled on the plate for contact with the

opposite side of the casing, and a roller journaled on the plate beyond the casing. 20

2. A fire stop or trap for motion picture machines, comprising a casing, an arcuate plate extending longitudinally of the casing and projecting beyond one end thereof, a flange on the end of the plate within the casing for contact with one wall of the casing, means pivoting the plate to such wall of the casing, a spring interposed between such wall of the casing and the plate, rollers 25 journaled on the concave side of the plate for contact with the opposite wall of the casing, and a roller journaled on the concave side and outer end of the plate. 30

In testimony whereof I affix my signature.

DON A. RAYMOND.
